CONTAINER CAPPING MACHINE

John J. Gaynor, Delphi, Ind., assignor to Horix Manufacturing Company, Pittsburgh, Pa., a corporation of Pennsylvania

Original application January 10, 1931, Serial No. 507,890. Divided and this application January 12, 1932. Serial No. 586,124

7 Claims. (Cl. 226—84)

This invention relates to the filling and capping of containers, and more particularly to mechanism for placing a cap on a container by automatically actuated capping mechanism.

5 This application is a division of application Serial No. 507,890, filed January 10, 1931.

One object of my invention is to provide in combination with a capping device a conveyor for bringing containers, hereinafter referred to 10 as bottles, into position to be capped, and timing means for controlling the actuation of the capping device in accordance with movement of a bottle on the conveying means.

A more specific object of my invention is to 15 provide in combination with a bottle filling machine a capping device arranged to cap a bottle when the bottle is brought beneath the same, said capping device being actuated by mechanism including a trip clutch which trips when a bottle 20 moves into position to be capped.

In order to illustrate these and other objects of my invention which will become apparent in the course of the ensuing description, I have illustrated in the drawings one embodiment which 25 my invention may assume.

In the drawings which are not intended to limit the invention to the particular embodiments shown,

30 Fig. 1 is a view in elevation of a filling machine combined with capping mechanism arranged to cap a bottle as it passes from the filling machine;

Fig. 2 is a detail view with parts broken away 35 to facilitate illustration of the capping device and actuating mechanism therefor;

Fig. 3 is a view of the mechanism shown in Fig. 2, taken at right angles to Fig. 2;

Fig. 4 is a sectional view on the line IV—IV 40 of Fig. 3;

Fig. 5 is a sectional view on the line V—V of Fig. 2;

Fig. 6 is a plan view showing the actuating cam and lever for the capping mechanism, this view being taken on the line VI—VI of Fig. 1;

45 Fig. 7 is a detail view on an enlarged scale of a portion of the mechanism shown in Fig. 2, but showing the capping device in raised position;

Figs. 8 and 9 are sectional views on an enlarged 50 scale, showing the jaw members of the clutch in closed and open positions respectively.

The filling machine which is shown only fragmentarily in Fig. 1 may be of any well known type. There is shown in broken lines, in Fig. 55 1, the tank 9 below which are arranged the fill-

ing heads 10. A hopper 11 is adapted to discharge caps through a chute 12 to be fed to the capping device. The hopper and chute are supported on standards 13 braced by an upper cross member 14 and a lower platform 15, forming a frame in which the tank is mounted for rotation. A rotating table 16 is mounted above the lower platform 15 and is driven by suitable actuating mechanism not shown. This table comprises a plurality of stirrups 17 (see Fig. 5), each stirrup being elevated and lowered by suitable elevating means 18. This elevating means may comprise a cam or track which controls the position of the stirrups 17 during rotation of the table.

The bottles are fed to the table of the filling machine from a conveyor 20 moving across the front of the machine. A guide 21 deflects bottles from the conveyor 20 and a star wheel 22 properly times the delivery of each bottle onto a stirrup 17 of the filling machine. On each stirrup 17 is a bottle guiding and positioning yoke 24 which centers the bottle on the stirrup. The two arms of the yoke 24 diverge so that the bottle may be pushed onto the stirrup 17 by the star wheel 22.

At the discharge point of the filling machine is a stationary support 25 to which is secured a guide finger 26. This finger projects angularly inwardly so as to deflect bottles from the stirrups 17 onto the support 25. The yokes pass in succession over the finger 26. The following arm of each yoke 24 cooperates with the finger 26 to move the bottle off of the stirrups 17 onto the support 25. Since the details of the filling machine do not enter into the present invention, they have been omitted from the drawings and are not described in this specification.

The capping mechanism may be of the type adapted to apply a screw cap if the neck of the bottle is provided with screw threads. Where catsup bottles or the like are being filled, the capping device may be of the type adapted to apply crown caps. Certain aspects of my invention are broadly applicable to these and other types of cap applying devices, and it is to be understood that I do not limit my invention to the particular type of cap applying devices illustrated in the drawings. These cap applying devices, however, have a cap receiving recess in which the cap is disposed when it is applied to the bottle. The cap applying device is then actuated so as to apply the cap to a bottle, and is again supplied with a cap by having such cap placed in the cap receiving recess. This cycle is repeated as often as a bottle is presented to be capped.

110

In the drawings, and more particularly in Figs. 2, 3 and 4, I have shown a crown cap applying device including a spring pressed plunger disposed above a die block as is customary in crown 5 capping machines. The die block has a lateral opening 28 (see Fig. 4) through which caps enter the cap receiving recess 29. In this form of capping device, the cap receiving recess is directly beneath the spring pressed plunger of the capping 10 device.

The chute 12 has a flexible portion which is connected to a curved portion 30 secured to the side of the capping device. The opening 28 is a lateral opening and, therefore, caps must be 15 deflected from their path down the chute in order to enter the cap receiving recess 29. The weight of the column of caps in the chute 12 is taken by an abutment member 32 at the lower end of the curved portion 30 of the chute; and at this time 20 the lowest cap in the chute is in line with the cap receiving recess 29.

I have provided mechanism, described and claimed in the parent application, for pushing this lowermost cap laterally from the chute into 25 the cap receiving recess 29. This mechanism comprises a swinging arm 33 having at its lower end a head 34 for engaging the cap. This swinging arm is pivoted at 35 to a bracket 36. Its upper end is provided with a crank 37 formed with an 30 arcuate slot 38. A pin 39 which is supported by a bracket 40 extends into the slot 38. The bracket 40 is carried by a vertical rod 41, slidably mounted in lugs 42 and 43. A compression spring 45 extends between the lower lug 43 and the 35 bracket 40, thus tending to move the bracket 40 upwardly.

The rod 41 is yieldably pressed downwardly relative to the capping device when a spring 40 pressed plunger 47 engages the upper cross member 14. The plunger 47 is slidable within a bore 48 in the rod 41 and is pressed upwardly by a spring 49. When the cap within the capping device has been applied to the bottle, the capping device rises, bringing the spring pressed plunger 45 47 into engagement with the cross member 14. This lowers the bracket 40, swings the arm 33 inwardly, and causes the lowermost cap in the chute to be pushed by the head 34 into the cap receiving recess 29.

As is apparent from Fig. 1, the capping device 50 is normally maintained in elevated position by a coiled spring 50 suspended by hook 51 from the upper cross member 14. The lower end of the spring 50 is attached to a jaw carrying member 53 of a trip clutch generally indicated by the 55 numeral 52. A pin 54 secures a rod 58 to the clutch member 53, the rod 58 extending vertically along the axis of the clutch member 53. A threaded sleeve 55 surrounds the rod 58 and is 60 slidably relative thereto; but normally the sleeve 55 is positioned as shown in Figs. 1 and 2 with its lower end bearing against the upper end of the clutch member 53. By rotating the threaded sleeve 65 relative to the capping device, vertical adjustment of the capping device is effected; as the capping device comprises a portion which surrounds the sleeve 55 and threadedly engages the same. A lock nut 54a is provided for securing the capping device in adjusted position.

The clutch member 53 is provided with a central longitudinal bore 56 within which the upper end of a rod 57 is slidable. The rod 57 forms part of actuating mechanism for the capping device. 75 This rod 57 is reciprocated at a regular rate; and the trip clutch is provided with the purpose of

causing the capping mechanism to reciprocate with the rod 57 when this clutch is tripped. The lower end of the rod 57 is slidable in a bearing 59. A block 60 provided with trunnions 61 is secured to the lower portion of the rod 57 above the bearing 59. The trunnions 61 are disposed in slots 62 in the two forks 63 on the end of a lever 64. The lever 64 has a pivoted mounting 65. A shaft 66 rotatably mounted in bearings 67 carries a cam 68 for actuating the lever 64. The latter carries intermediate its ends a roller 69 against which the cam 68 bears. A bevel gear 70 on the inner end of the shaft 66 meshes with gear teeth 71 on the underside of the rotating table 16. It is apparent, therefore, that as the table 16 is rotated, the shaft 66 drives the cam 68 so as to depress the block 60. The block 60 is secured to the rod 57 so that the latter is forced downwardly. Return movement of the rod 57 to its upper position is brought about by a suitable counter-weight or by resilient means not shown.

The capping device is not rigidly connected to the clutch member 53 by the rod 58; but instead, the sleeve 55 is slidable on the rod 58 and resilient means are provided for connecting the 100 capping device to the rod 58 so that instead of smashing a bottle, if an unusually tall one is being capped, or if, for any reason, the cooperation of parts of my improved mechanism of the capping 105 device is imperfect, the connection between the capping device and the rod 58 will yield. This yieldable connection comprises a compression spring 75 bearing with its lower end against the upper end of the sleeve 55 and surrounding the upper portion of the rod 58. A nut 73 engages the upper end of the spring 75 and is locked in 110 adjusted position by a lock nut 74.

Tripping of the clutch 52 is brought about through the inward movement of a pair of pivoted jaw members 76 mounted in slots in the 115 sides of the clutch member 53. These slots extend clear through the clutch member 53 so that the jaw members may enter the bore 56 when swung inwardly. At 78 (as indicated in Fig. 2) the rod 57 is provided with a peripheral groove 120 having shoulders 79 and 80. The edges of the upper end of the rod 57 are beveled as indicated at 83, so that the pivoted jaw members will be wedged apart to admit the upper end of the rod 57, should the latter be elevated while these jaw 125 members are contracted. The jaw members 76 are urged inwardly by leaf springs 85 secured to the sides of the jaw carrying member 53. The jaw members 76 are each pivoted at one end to the jaw carrying member 53 as indicated at 86 (see Fig. 3). A wedge member 87 cooperates with the other ends of the jaw members to separate the same except when the capping device is to be actuated. It is apparent, therefore, that so long as the wedge 87 is removed from the position 130 shown in Fig. 1 so that the leaf springs 85 may force the jaw members 76 inwardly, these jaw members will engage in the groove 78 so as to clutch the member 53 and the capping device mounted thereon to the rod 57. The reciprocations of the rod 57 are, therefore, transmitted to the capping device and the spring 50 is elongated each time the capping device is pulled downwardly. This spring 50 accordingly acts to return the capping device to its upper position. A dash pot 88 acts to cushion the return movement 135 of the capping device.

The wedge 87 is carried on one end of a bell crank lever 89 pivotally mounted at 90 on the support 25. A coil spring 91 tends to return this 140

bell crank lever to the position indicated in Fig. 5. An arm 92 of the bell crank lever 89 projects into the path of the bottles being pushed from the stirrups 17 onto the support 25. Each time 5 a bottle moves along the finger 26 it engages the arm 92 and rocks the bell crank lever 89 so as to remove the wedge 87 from between the jaw members 76. It is apparent, therefore, that each time a bottle is delivered onto the support 25 the clutch 10 52 is tripped. Should no bottle be delivered from a stirrup 17, the clutch is not tripped and the jaw members 76 remain separated. The rod 57 accordingly moves downwardly relative to the member 53 without pulling the capping device 15 downwardly with it.

The operation of my improved mechanism is as follows: Bottles are fed along the conveyor 20 and are deflected by the deflecting guide 21 and the star wheel 22 onto the stirrups 17 of the 20 filling machine. The bottles are then filled from the filling heads 10; and when each stirrup comes around to a position adjacent the support 25, the bottle is ready to be discharged from the filling machine. Such discharge takes place because of the engagement of the finger 26 with the bottles 25 so as to crowd the same between the finger 26 and the following arm of the yoke 24 on the stirrup 17. This forces the bottle against the arm 92 and trips the clutch 52 just as the bottle 30 is being pushed beneath the capping device. Capping accordingly takes place immediately at the point of discharge from the filling machine onto the stationary support 25. The clutch having been tripped, the capping device is carried 35 downwardly by the rod 57 so as to place a cap on the top of the bottle.

If the next stirrup 17 is empty, the wedge 87 is 40 permitted to return and remain in position between the jaw members 76, and the capping device is accordingly not actuated until another bottle is forced off a stirrup onto the support 25. The pushing of this succeeding bottle onto the support 25 pushes the preceding bottle out from the capping device. Guides 94 are provided for 45 guiding the capped bottles back onto the conveyor 20.

It is apparent from the above description that the improved capping mechanism which I have 50 invented has the advantage that the same is not actuated unless a bottle is delivered into position to be capped. This advantage is in part due to the trip mechanism which causes the clutch to bring about actuation of the capping device when a bottle is delivered beneath the capping device. 55 A further advantage of my invention resides in the arrangement for capping a bottle immediately upon its delivery from a filling machine onto a support beneath the capping device. It will furthermore be understood that there is additional 60 advantage in the provision of the automatic control for the actuation of the capping device in such an arrangement since a bottle is delivered onto the support and immediately capped, and the capping mechanism does not again descend 65 until the capped bottle has been pushed out from beneath the capping device by the delivery of the next succeeding bottle from the filling machine.

Certain advantages arising as a consequence of 70 the improvements I have provided in a capping device by my invention are not restricted to the combination of the capping device in the manner illustrated in the drawings with a filling machine, nor in fact with any particular apparatus. It is 75 to be understood, therefore, that from certain aspects, my invention is broadly applicable to cap-

ping devices, whether constructed as separate units, or whether used in any of a variety of combinations.

The terms "cap" and "capping mechanism" and the like, as used throughout the specification and 80 claims are used generically as terms of definition and not limitations, and are inclusive of closures, crowns and caps generally regardless of their specific type or construction.

While I have illustrated and described one specific form of bottle capping mechanism and one particular arrangement of bottle filling machine and bottle capping mechanism, it will be understood that the invention is not restricted to the particular construction and arrangement shown, 90 but may be variously modified within the contemplation of the invention and under the scope of the following claims.

I claim:

1. In a closure applying machine, a capping device, positive means for moving a container to operative position beneath the capping device, actuating means for the capping device, and means controlled by movement of a container toward operative position for rendering said actuating 100 means operative, said controlled means being engaged by a container only during movement of a container toward operative position but disengaged from such container at operative position.

2. In a closure applying machine, a closure applying device, means for moving a container to operative position beneath the closure applying device, actuating means for lowering said closure applying device to apply a closure to a container, and control means engaged by a container in 110 moving toward operative position for rendering said actuating means operative, said control means being disengaged from a container which has reached operative position.

3. In a closure applying machine, a closure applying device, means for moving a container to operative position beneath the closure applying device and permitting a dwell of such container in operative position, actuating means for the closure applying device, and means controlled 115 by movement of a container toward operative position for rendering said actuating means operative, said controlled means being engaged by a container only during movement of a container toward operative position but disengaged 120 from such container at operative position.

4. In a container closing machine, a device for fixing a closure to a container to seal the same, means for moving a container toward operative position beneath said device while a container 130 is in such operative position, actuating means for said device, and a trip for timing the sealing operation of said device, said trip being controlled by engagement therewith by a container moving toward operative position and being disengaged from the container when the same reaches operative position.

5. In combination, a container filling machine, a closure applying device, means for transferring 140 the filled containers in succession from the filling machine to operative position beneath the closure applying device and permitting each container to dwell in operative position for the interval between the discharge of successive containers from the filling machine, actuating means for said closure applying device, and a trip engageable by a container moving toward operative position for rendering said actuating means operative, said trip being disengaged from a container which is in operative position.

6. In combination, a container filling machine of the rotary type having a rotatable carrier for the containers, a support for receiving a container from the filling machine, means for transferring the filled containers in succession at a predetermined station from the carrier of the filling machine to said support, a closure applying device arranged to close a container supported on said support, means for actuating said closure applying device, and timing means engaged by a container while being moved along by said transfer means for controlling said actuating means.

7. In combination, a container filling machine of the rotary type having a rotatable carrier and guides thereon for the containers, a support for receiving a container from the filling machine, a guide for deflecting filled containers in succession from the carrier of the filling machine onto said support, a closure applying device arranged to close a container supported on said support, means for actuating said closure applying device, and a trip engaged by a container while being deflected from said carrier for timing the actuation of said closure applying device.
